D. 649
5-23-1854

Des. 649

G. Smith, H. Brown & J. A. Read of Philadelphia, Pa.
Assignors to Abbott & Lawrence of same place.
Letters Patent No. 649 Dated May 23d, 1854.

The schedule referred to in these Letters Patent, & making part of the same.

To all whom it may concern.

It is known that we, Garrettson Smith, Henry Brown & Joseph A. Read, of the City and County of Philadelphia, and State of Pennsylvania, have invented a new and original design for Portable Range, and we do hereby declare that the following is a full, clear and exact description of the same; reference being had to the annexed drawings, in which.

Figure 1 is a front elevation of the stove; and

Figure 2. an end elevation of the same.

Similar letters of reference denote the same part of the stove and design.

The design of this stove consists in the embellishments in bas-relief on its front and ends. The front has at each end the needed pilasters A, and bears the panel B, and oven door C, raised by the mouldings D; the latter embellished by the ornament E in bas-relief, consisting of the figures, having the foliage A issuing from each corner; the configuration and arrangement of the whole being as represented in figure 1.

The ends are represented by figure 2, one having a draft door D, and the other simply the panel B; each of the panels bears the bas-relief ornament E, having the design configuration and arrangement set forth in figure 2.

In the several figures symmetrical designs have but one half of their details shown.

What we claim as our invention or production and desire to secure by Letters Patent, is the design, configuration, and arrangement of the ornaments in bas-relief on the front and ends of the stove as herein described, and set forth in the annexed drawings forming a new and original design for stove called Portable range.

In testimony whereof, we have hereunto signed our names before two subscribing witnesses:
